[57] CLAIM

The ornamental design for a lamp with pivoting magnifier, as shown and described.

DESCRIPTION

FIG. 1 is a side elevational view of my design for lamp with pivoting magnifier;

FIG. 2 is a fragmentary bottom plan view of my design for lamp with pivoting magnifier, the lamp being fragmentarily shown for convenience of illustration;

FIG. 3 is an end elevational view of my design for lamp with pivoting magnifier;

FIG. 4 is a perspective view of my design for lamp with pivoting magnifier; and,

FIG. 5 is a perspective view of my design for lamp with pivoting magnifier similar to FIG. 4 with the magnifying element pivoted to another operative position.
